METHOD OF AND APPARATUS FOR
BLOCKING HATS

Rudolph G. Segschneider, Yonkers, N. Y.

Application July 24, 1930. Serial No. 470,410

7 Claims. (Cl. 223—31)

My present invention relates to machines and methods employed in the blocking of hats, and particularly to the blocking of hats of felt and analogous materials in which a brim stretching operation is performed.

Heretofore, in the dry or finish blocking operation on hats as carried out in a manually controlled hat blocking machine, it has been the practice to initially position a rough blocked hat 10 in a removable banding ring of fixed dimensions with the hat crown extending downwardly through the ring, the banding ring used being determined by the desired final crown size of the finished hat. The hat brim is then gripped about 15 its periphery by suitable clamping members and the hat material softened for the subsequent operations by passing steam into contact therewith. The clamping members are then moved outwardly to stretch the brim in a radial direction. The 20 material of the hat being in a softened condition and no resistance other than that of the material itself being offered to the brim stretching forces, the hat is quickly stretched to the desired brim outer edge dimension. With the brim firmly 25 held in this position, a crown blocking operation is then carried out by inserting a crown block, corresponding in size with the banding ring used and in contour to the desired final crown contour, through the banding ring and forcing this block 30 downwardly into the crown. This operation causes an annular portion of the crown previously outside the banding ring to be pulled over the edge of the ring, and causes further stretching of the material in the hat brim. The crown block 35 must be forced into the crown a greater distance than the finished size of the hat requires to compensate for the elasticity of the material stretched. The brim is then released and the hat with the crown block in position is removed from 40 the machine for the subsequent finishing operations.

I have discovered certain disadvantageous features of the above described blocking method which impair the quality of the hats operated 45 on, increase the time and labor expended in the process, and cause a relatively rapid replacement of certain parts of the machine used. For example, in the above method, the lack of substantial resistance to the initial stretching of the brim 50 requires that the major portion of the brim stretching actually be effected during the crown blocking operation in which the material is again pulled over the upper edge of the band ring. By this action, certain annular portions of the hat 55 adjacent to the line of juncture of the brim and

crown are subject to substantial strain and wear by their movement back and forth over the banding ring upper edge. In my improved method hereinafter described, the stretching of the brim is substantially completed by the outward movement of the clamping members by providing a substantial resistance to any movement of the crown material over the banding ring edge, thereby confining the stretching in the brim stretching operation to the brim material, minimizing 60 the area of the material contacting with the brim edge, and substantially lessening the amount of wear due to such contact.

In the former method, the banding ring used is of fixed dimensions corresponding to the desired crown size. With such a ring in position, its relatively sharp upper edge will exert a substantial wearing contact on any material drawn thereover, particularly since the pull is exerted perpendicularly to the direction of movement of 70 the crown material. Increasing the resistance to the material movement would correspondingly increase the wear on that portion of the material contacting with the ring edge. In accordance with my improved method, the banding ring is 75 made expandable and usually arranged in a somewhat expanded position during the brim stretching operation to increase the angle between the direction of the brim stretching forces and the direction of movement of any material, thereby 80 acting in conjunction with the crown block to lessen the wear caused by contact with the ring edge.

An expandable banding ring is also advantageous as by its use the need for a number of 85 banding rings for each size of crown block is avoided, the expenditure of time and labor in replacing the ring then in use by a different size for hats of another size is eliminated, and the possibility of use of band rings distorted by previous use and the consequent production of hats 90 of inferior quality, is avoided. An expandable banding ring further permits the blocking of hats having crown dimensions greater than the maximum banding ring dimension without decreasing 95 the quality of the bands formed thereon. Moreover, the permissible expansion of the banding ring for the passage of the crown block during the crown blocking operation substantially eliminates the stress and wear on the material here- 100 tofore compressed between the fixed banding ring and crown block, which stress frequently results in tearing of the hat along the base of the crown.

A main object of my invention is the provision 105 of a method of dry blocking hats which is charac- 110

terized by the uniformity of the results attained, a decrease in the amount of wear on the hat during the operations, effecting substantially all of the stretching of the brim before the crown 5 blocking operation is performed, and a greater restriction and distribution of the strains occurring during the brim stretching and crown blocking operations to the respective portions of the hat then being treated. Another principal object of my invention is the provision of a hat blocking machine which is adapted to be manually operated to efficiently carry out my improved blocking method and characterized by its capacity for operation on hats of different sizes 10 and shapes with no changes in the operating parts, and by the simplicity of its construction and mode of operation.

The various features of novelty which characterize my invention are pointed out with particularity in the claims annexed to and forming a part of this specification. For a better understanding of the invention, however, and the advantages possessed by it reference should be had to the accompanying drawings and descriptive 25 matter in which I have illustrated and described a preferred embodiment of the invention.

Of the drawings:

Fig. 1 is a plan view of a preferred embodiment 30 of my invention;

Fig. 2 is a vertical section on the line 2—2 of Fig. 1;

Fig. 3 is an elevation of the apparatus shown in Figs. 1 and 2; and

Fig. 4 is an enlarged detail view partly in section showing some of the machine parts in one 35 of their operating positions.

Referring now to the drawings wherein like reference numerals designate corresponding parts throughout the several views, 5 designates the top and 6 the bottom of a substantially square shaped, upright frame 7 supported from the floor by corner legs or supports 8, said frame being preferably made of metal to form a rigid support for the operating mechanism.

45 Adjacent the open top of the frame, there is provided a flanged ring 9 permanently fastened to the inside of the frame, said ring supporting a frusto-conical chamber or pot 10. Referring particularly to Fig. 2, it will be noted that the frame also includes a central, horizontal partition 11 preferably integral therewith, which partition supports a central stationary column 12 having a vertical reduced section 13. The column section 13 is arranged to receive a vertically 50 slidable circumferentially grooved collar 14.

Secured to the upper end of the column 13 is a plate 15 on which rest flat horizontal arms 16, 17 of a pair of movable L-shaped brackets 18, 19 and similar arms 20, 21 of a second pair of brackets 22, 23, which have two substantially semi-circular banding ring sections 24, 25 fixed on their upper ends, each ring section being flexible to permit of movements of approach and separation of its two ends. The top portions of the brackets 18, 19 are formed with segment sections 26, 27 to which are fixed guide segments 26a, 27a on their inner sides forming grooves or guides receiving the free ends of the ring sections 24, 25 for sliding movement therein.

70 The ring sections 24, 25 may be expanded and retracted relative to a hat block by mechanism hereinafter described. Each horizontal arm of the brackets 16, 17, 20, 21 carries a short pin 30 which extends through a corresponding obliquely arranged segmental cam slot 31 in a partly ro-

tatable circular plate 32 mounted on a central stud or pin 33 and arranged to permit inward or outward radial movement of said arms to simultaneously contract or expand the ring sections 24, 25. It will thus be seen that since the 80 segmental slots 31 in the plate 32 are not concentric to the pivot on which the plate is mounted, a clockwise rotation of said plate will cause the brackets to be expanded and a counterclockwise rotation cause the brackets to retract. To 85 accomplish this operation, a rod 34 is fastened at one end 35 to the plate and the opposite end 36 of the rod is connected to one leg of a bell crank lever 37, pivoted at 38, and the other leg of which serves as an operating handle. The curved form 90 of the cam slots is advantageous in providing a partial locking effect on the banding ring sections when the pins 30 are in their innermost positions.

Again referring to Fig. 2, it will be noted that 95 the frame partition 11 carries a plurality of posts 39 on which is mounted an annular plate 40, which carries a series of fixed horizontal arms 41, each forming a pivot 42 for a bell crank lever 43 arranged to form the lower jaw member of a 100 brim clamp. The lower leg 44 of each lever is inclined downwardly towards the collar 14 and terminates in a boss 45 which fits within the groove 46 of the collar. The vertical legs 47 of the levers extend upwardly to a point on the 105 same level with the top of the banding ring.

In order to move the levers 43 above their pivots 42 the collar 14 is equipped with a pair of depending brackets 50, 51 fixed thereto and passing through openings in the partition 11. The 110 lower ends of these brackets are connected by arms 52 to a rock shaft 53, mounted on extensions 54 depending from the sides of the frame. Keyed to the shaft 53 is a segmental gear 55, arranged to mesh with a second segmental gear 56 115 on a stub shaft 57, which is rotatable by a lever 58 rising vertically above the top of the frame. The lever is equipped with a releasable spring lock or catch 59 cooperating with a segmental toothed rack 60 fastened to the side of the 120 frame, as shown in Fig. 4.

Cooperating with the brim clamp levers 43 are a series of clamping fingers 61 reciprocably mounted in the levers 43 and having their lower ends passing through slots 42a in the corresponding arms 41 and pivoted at 62 to a vertically movable ring 63 located at the outside of a steam pot 64, which is secured to the partition 11 by an angle bar 64a. The clamping surface 65 of each finger 61 is located above the clamping surface 65a of the corresponding lower jaw member so that when the ring 63 is lowered, the peripheral portion of a hat brim 66 positioned therebetween will be firmly clamped.

The vertically movable ring 63 is normally held 135 in its raised position by means of coiled spring members 67 arranged between the partition 11 and the ring. Attached to the bottom of the ring are a pair of angle members 68 having links 69 fastened thereto, the lower end of each link being 140 connected to a corresponding lever 70 on a shaft 70a. The shaft is actuated by connecting one of the levers through a link 71 to a bell crank actuating lever 72 pivoted to the frame at 73 and terminating in a handle. Stops 69a on the links 145 69 limit the upward movement of the ring 63 under the action of the springs 67. By this arrangement the fingers 61 may be actuated independently of the lower jaw members 43 to release or clamp the hat brim. A circular coil 150

spring 74 is provided to aid the return of all of the brim clamp members to their inner position when the operating lever 58 is released.

To introduce steam for softening the hat material, I provide a steam pipe 75 having branches 76 which pass through the partition 11 into the steam pot 64. The steam is controlled by means of a suitable valve 77, which may be opened and closed by means of a foot lever 78, link 79, and a valve operating lever 80, arranged in a well known manner.

A presser block 81 pivotally carried by an operating bar 82, pivoted at 83 to a bracket 84 on the machine frame is normally held in a raised position by a tension spring 85 extending between an eye 86 in the bar extension 88 and a frame pin 87. The presser head and lever is adapted to be actuated by the operator to engage the top surface of the crown block 48.

Having described the structural features of my invention, the mode of use of the machine will now be set forth. In the blocking of felt hats for example, a crown block of the desired final size and contour of the hat crown is initially inserted in the crown, extending downwardly therein to a substantial extent. The hat with the crown block in position is then arranged by the operator with the crown positioned within the banding ring 24 and its brim resting on the upper edge of the ring and between the jaw and finger members of the brim clamps. The machine parts are then in the position illustrated in Fig. 2 except that the banding ring sections are partly expanded. In this position the lower brim surface contacts with the flat upper surfaces 65a of the jaw member 43 and the brim peripheral portions extend below the lower surfaces 65 of the fingers 61. The operating handle 72 is then moved towards the operator to lower the ring 63, and thereby the clamping fingers 61, to firmly clamp the peripheral portions of the brim. The steam valve 77 is then opened to permit steam to discharge upwardly through the pot into contact with the exposed undersurfaces of the hat body and brim. The operating lever 58 is then moved towards the operator to raise the collar 14 and thereby move the jaw members 43 and clamping fingers 61 outwardly about their respective pivots 42 and 62, to stretch the hat brim. These parts are then locked in that position.

The brim clamps are sufficiently numerous and so distributed about the periphery of the brim that a uniform stress is exerted on all portions of the brim. The material stretched by this operation is almost wholly confined to the brim proper as the weight and position of the crown block restrict any upward movement of the material in the hat body over the upper edge of the banding ring. The limited movement of material over the upper edge of the banding ring and the arrangement of that member in its partly expanded position substantially avoids the extensive abrasive action on the material which would otherwise occur.

At or near the end of the brim stretching operation, the lever 37 is rotated to tighten the banding ring sections to a predetermined extent about the hat crown. The contracted banding ring will hold the corresponding portions of the crown against the crown block therein. The presser block is then lowered by the operator into contact with the crown block 48 and forced downwardly to move the crown block into its lowermost position, as illustrated in Fig. 4. During this

movement there will usually be a slight expansion of the band ring as the base portions of the block are generally slightly larger in cross section than the remaining block portions. This expandible feature of the ring substantially reduces the strain on the material confined between the moving crown block and banding ring. The banding ring is then fully contracted by the operator to complete the band forming section. The foregoing operations can be rapidly performed by the operator in substantially the sequence described and when accomplished, the steam supply is subsequently cut off and the hat withdrawn from the machine by expanding the banding ring and raising the clamping fingers 61. The crown block is left in position when the hat is withdrawn, as this arrangement is advantageous in carrying out the subsequent finishing operations on the hat.

While in accordance with the provisions of the statutes, I have illustrated and described the best form of embodiment of my invention now known to me, it will be apparent to those skilled in the art that changes may be made in the apparatus disclosed without departing from the spirit of my invention as set forth in the appended claims and that in some cases certain features of my invention may be used to advantage without a corresponding use of other features.

Having now described my invention what I claim as new and desire to secure by Letters Patent, is:

1. The method of dry blocking hats which comprises loosely mounting a hat body having a crown block of the desired final crown size and contour inserted therein to a substantial extent in an inverted position in a supporting and band forming ring, clamping the peripheral portions of the hat brim, subjecting the exposed under surfaces of the hat to the effect of steam in contact therewith, exerting a uniform stretching force on all portions of the brim while maintaining the crown portion of the hat in substantially its original position, tightening the band ring about the hat crown, forcing the crown block downwardly under a substantial pressure to define the crown and band with substantially no movement of the material over the upper edge of the banding ring.

2. The method of dry blocking hats which comprises loosely mounting a hat body having a crown block of the desired final crown size and contour inserted therein to a substantial extent in an inverted position in a supporting and band forming ring, clamping the peripheral portions of the hat brim, subjecting the exposed under surfaces of the hat to the effect of steam in contact therewith, exerting a uniform stretching force on all portions of the brim, tightening the band ring about the hat crown, forcing the crown block downwardly under a substantial pressure to define the crown and band, and subsequently expanding the banding ring and unclamping the brim to permit the removal of the hat with the crown block in position therein.

3. A hat blocking machine comprising a series of brim clamps arranged in spaced relation and formed by cooperating pivoted jaw and finger members arranged for a relative reciprocable movement to clamp a hat brim, means for relatively reciprocating said members, means for swinging said members outwardly about their pivotal points to stretch said brim, a banding ring positioned within said brim clamp series and formed by a pair of substantially semi-circular flexible ring sections the ends of each of which

- normally extend into close proximity with the corresponding ends of the other, said ring sections being normally arranged to loosely receive an inverted hat body with a crown block of the desired final crown size and contour partly inserted therein, means for relatively moving said ring sections to expand or contract said banding ring, said means comprising actuating members movable toward and away from one another in the direction of movements of approach and separation of the ends of each section relative to the other as the banding ring is expanded and contracted, and separate guiding means for each adjacent pair of ring section ends movable transversely to the first mentioned direction and positively guiding the four ends of the two ring sections in the contraction of said banding ring, a presser block, and means for forcing said presser block downwardly against said crown block to conform the hat crown to said crown block.
4. A hat blocking machine comprising a series of brim clamps arranged in spaced relation and formed by cooperating pivoted jaw finger members arranged for a relative reciprocable movement to clamp a hat brim, means for relatively reciprocating said members, means for swinging said members outwardly about their pivotal points to stretch said brim, a banding ring positioned within said brim clamp series and formed by a pair of relatively movable ring sections, said ring sections being normally arranged to loosely receive an inverted hat body with a crown block of the desired final crown size and contour partly inserted therein, means for relatively moving said ring sections to expand or contract said banding ring comprising a pair of supporting brackets fixed thereto, a second pair of brackets slideably connected thereto and means for radially moving said brackets, a presser block, and means for forcing said presser block downwardly against said crown block to conform the hat crown to said crown block.
5. A hat blocking machine comprising a series of brim clamps arranged in spaced relation and formed by cooperating pivoted jaw and finger members arranged for a relative reciprocable movement to clamp a hat brim, means for relatively reciprocating said members, means for

swinging said members outwardly about their pivotal points to stretch said brim, a banding ring positioned within said brim clamp series and formed by a pair of relatively moveable ring sections, said ring sections being normally arranged to loosely receive an inverted hat body with a crown block of the desired final crown size and contour partly inserted therein, and means for relatively moving said ring sections to expand or contract said banding ring comprising a pair of L-shaped supporting brackets fixed thereto, a second pair of L-shaped brackets slideably connected thereto, rotatable plate having a plurality of cam slots formed therein, pins on said brackets engaging in said slots, and means for rotating said plate.

6. A hat blocking machine comprising a banding ring formed by a pair of relatively movable ring sections, said ring sections being arranged to receive an inverted hat body with a crown block of the desired final crown size and contour partly inserted therein, and means for relatively moving said ring sections to expand or contract said banding ring comprising a pair of L-shaped supporting brackets fixed thereto, a second pair of L-shaped brackets slideably connected thereto, a rotatable plate having a plurality of cam slots formed therein, pins on said brackets engaging in said slots, and means for rotating said plate to cam said brackets outwardly or inwardly.

7. A hat blocking machine comprising a banding ring formed by a pair of relatively movable ring sections, said ring sections being arranged to receive an inverted hat body with a crown block of the desired final crown size and contour partly inserted therein, and means for relatively moving said ring sections to expand or contract said banding ring comprising a pair of L-shaped supporting brackets fixed thereto, a second pair of L-shaped brackets slideably connected thereto and means for radially moving said brackets, a presser block, and means for forcing said presser block downwardly against said crown block to conform the hat crown to said crown block.
